COMBINATION TAPE STORAGE AND SPEAKER ENCLOSURE

Fred C. Kossen, Jr., 1211 N. Siesta,
Anaheim, Calif.

Filed Oct. 14, 1975, Ser. No. 621,942

Term of patent 14 years

Int. Cl. D14—01

U.S. Cl. D26—14 G

FIG. 1 is a perspective view of my new design for a combination tape storage and speaker enclosure;

FIG. 2 is a top plan view thereof;

FIG. 3 is an rear-elevation; and

FIG. 4 is a bottom plan view thereof.

I claim:

The ornamental design for a combination tape storage and speaker enclosure, as shown and described.
